UNITED STATES PATENT OFFICE

CHARLES WILD, OF EUREKA, CALIFORNIA

CORE BREAKER AND HOISTER

Application filed October 27, 1927. Serial No. 229,147.

This invention relates to mechanism for use in well drilling and is especially designed to be used in connection with the well drill patented Sept. 27, 1927, No. 1,643,730, or with the well boring machine patented Sept. 27, 1927, No. 1,643,731. These machines operate to drill an annular shaped hole to a certain depth and then be withdrawn from the well, leaving a central core. The core, if the well 10 is drilled through solid rock, must be broken off at the bottom of the hole before it can be removed, but if the well is drilled through soft or disintegrated material the core is often a mass of loose material which must be scooped up for removal to the surface of the ground. Drilling a well is accomplished by the alternate use of the drilling device and the core remover.

The object of the present invention is to 20 provide means for removing to the surface of the ground, the solid core or the loose material remaining at the bottom of the hole formed by the well drilling machine, of the character mentioned, after the said machine 25 has been removed from the hole.

An important object of the invention is to provide a device of the character described, which may be operated with facility, and one which will operate to grip and retain the 30 core material after breaking said core off, or scooping it up, when the device moves upwardly after it has reached the bottom of the hole formed by the well drilling machine.

With the foregoing and other objects in 35 view which will appear as the description proceeds, the invention resides in the combination and arrangement of parts and in the details of construction hereinafter described and claimed, it being understood that 40 changes in the precise embodiment of the invention herein disclosed, may be made within the scope of what is claimed, without departing from the spirit of the invention.

Referring to the drawings:—

Fig. 1 is a vertical section through the cage of a device constructed according to this invention, showing two shovels and their operating devices in the locked position, other parts being omitted for clearness. Fig. 2 is 50 a plan view, from above, of the complete

device. Fig. 3 is a sectional plan view, taken on the line 3—3 in Fig. 1. Fig. 4 is a view similar to Fig. 1, but shows the shovels unlocked and operated so as to engage the material between them. Fig. 5 is a sectional plan 55 view taken through the cage on the line 5—5 in Fig. 4. Fig. 6 is a detail view of one shovel. Fig. 7 is a detail side view of a portion of the cage showing the parts 5, 8, 15, and some other parts. 60

Referring to the drawings in detail, the device includes a cage formed of pairs of vertical bars 5, arranged in spaced relation with each other, the upper ends thereof being connected by means of the spider 6, while the 65 lower ends are connected with the ring 7.

Mounted between each of the pairs of bars 5 is a pair of bars, the lower extremities of which are indicated at 8, the upper extremities 9 are curved inwardly and provide a 70 support for the arms 10. The lower ends 8 of the bars extend below the bottom of the cage as shown by Figure 1 of the drawings.

The bars 8 are provided with elongated openings 13 in which the pivot pins 14 move 75 the pivot pins providing means for pivotally connecting the arms 15 of the breaker points or shovel sections 16 with the bars 5, the upper extremities of the arms 15 being curved inwardly, as shown by Figure 1 of the 80 drawings.

Connected pivotally with the inwardly curved upper extremities of the arms 15 are vertical arms 17 which are connected with the angularly disposed arms 18, at 19, the upper 85 ends of the arms 18 having pivotal connection with the pairs of cage bars 5, at 20, arms 21 have pivotal connection with arms 18 between the end connections 19 and 20, and extend to and have pivotal connection with the head 22, at 23, the head being connected with the rod 24, and held thereto by means of the nut 25, the rod 24 operating through a square opening in the spider 6. The upper end of the rod 24 is formed with an opening 26 to 90 accommodate a suitable cable or other flexible member whereby the device may be raised or lowered within a well.

Mounted between each pair of bars 5 is an arm 10, pivotally secured thereto at 20, and 100

extending to and resting, upon the upper ends of the breaker or shovel arms 15. The arms 10 have elongated openings 11 to accommodate the pivot pins 12 which connect the said arms with the bars 8 so that the arms 10 may move slightly over the pivot pins 12. Figure 1 shows the arms 10 resting upon the upper end portions of the arms 15 so as to lock the arms 15 and prevent movement of the breaker sections 16 relative to the cage. The arms 10, through the action of the bars 8, move out of contact with the arms 15 when the cage rests upon the bottom of the hole. Figure 4 shows arms 10 out of contact with the arms 15.

The breaker sections or shovels 16 are so constructed that when they are brought into cooperative relation with each other, they will not only scrape the bottom of the hole, but will act to pick up the material scraped thereby to the end that when the device is elevated, the breaker sections or shovels 16 will carry with them the core, or the material left in the bottom of the hole by the well drilling device.

In the use of the device, the device is lowered into a well hole until it reaches the bottom thereof, whereupon the device operates to unlock the core breaker arms so that they are free to move on their pivot connections and upon the device being lifted by the cable, the breaker sections or shovels swing inwardly to the positions shown by Figure 4 of the drawings, to the end that the material in the bottom of the well hole will be picked up and carried above the surface of the ground, where an especially designed mechanism, forming the subject matter of a separate application to be filed, operates to hook under the spider at the upper end of the core breaker and hold the device in suspension so that when the lifting cable or rope is slackened sufficiently, the moving parts of the core breaker assume their original locked positions and at the same time the core material is released and discharged into the hopper or chute of the above mentioned especially designed mechanism, which operates to move out of the way when the core breaker is adjusted to enter the upper end of the casing and be again lowered to the bottom of the well or prospect hole.

I claim:—

1. In a device of the character described, 55 pairs of spaced vertical bars, a spider for connecting the upper ends of the bars, a circular band member for connecting the lower ends of the bars, pairs of bars slidably supported between the bars of the first mentioned pairs 60 of bars having inwardly extended upper end portions, the lower portions normally extending below the bottom of the cage, elongated openings in the bars, the bars being adapted to move throughout the lengths of the elongated openings, bars pivotally supported be-

tween the pairs of the last mentioned bars and having inwardly extended upper end portions and lower portions carrying shovel sections, locking arms pivotally supported between the pairs of spaced vertical bars of the cage, elongated openings in the locking arms, means having connection with the inwardly extended upper end portions of the first mentioned pairs of slidably supported bars, for moving the locking arms out of engagement with the inwardly extended upper end portions of the pivotally supported bars having shovel sections at their lower portions, means having connection with the inwardly extended upper end portions of the shovel bars for moving the shovel sections towards and away from each other.

2. In a device of the character described, a cage adapted to be lowered to the bottom of a well, pivoted bars carrying shovel sections at their lower ends mounted within the cage, and means for operating the pivoted bars to cause the shovel sections to move towards and away from each other, arms having pivotal connection with the supporting cage and having close contact with the upper ends of the shovel bars and adapted to operate to lock the shovel bars to prevent movement of the shovel bars with reference to the supporting cage, bars slidably supported by the cage and having pivotal connection with the locking arms and normally extending below the bottom of the cage, the sliding bars to operate to disengage the locking bars from contact with the upper ends of the shovel bars when the bottom of the cage rests upon a firm support such as the bottom of a well.

3. In a device of the character described, a cage, release bars slidably vertically in the cage at the sides thereof and normally projecting below the bottom of the cage, shovels provided with arms which are pivoted to the said cage, locking arms for the shovels pivoted to the cage and operatively connected with the release bars, and means for operating the shovels on their pivots when unlocked.

4. A device as set forth in claim 3, the said means for operating the shovels comprising lower arms pivoted to the shovel arms, upper inclined arms pivoted to the lower arms and to the cage, and a central lifting device operatively connected with the said upper inclined arms.

5. In a device of the character described, a cage provided with vertical bars arranged in pairs, pairs of release bars slidably vertically between the pairs of cage bars and normally projecting below the bottom of the cage, shovels provided with arms arranged between the release bars and pivoted to the cage bars, locking arms for the shovels pivoted to the cage bars and operatively connected with the said release bars, and means for operating the shovels on their pivots when unlocked.

6. A device as set forth in claim 5, the said release bars being provided with elongated openings which slide over the pivots of the shovel arms.

5 7. A device as set forth in claim 5, the said locking arms being provided with elongated openings which slide over the pivots of the upper end portions of the release bars.

8. In a device of the character described,
10 a cage, shovels provided with arms which are pivoted to the said cage and which have inwardly projecting upper end portions, lower arms pivoted to the said end portions, upper inclined arms pivoted to the lower
15 arms and to the cage, a central lifting device provided with a head, and arms pivotally connecting the said head with the said upper inclined arms.

In testimony that I claim the foregoing
20 as my own, I have hereto affixed my signature.

CHARLES WILD.
